(57) **CLAIM**

The ornamental design for a container with football game feature, as shown and described.

DESCRIPTION

FIG. 1 is an isometric view of the container with football game feature illustrated in an erected state;

FIG. 2 is an isometric view of the container with football game feature illustrated in a collapsed state;

FIG. 3 is a front elevational view of the design of FIG. 1;

FIG. 4 is a rear elevational view of the design of FIG. 1;

FIG. 5 is a right-side elevational view of the design of FIG. 1;

FIG. 6 is a left-side elevational view of the design of FIG. 1;

FIG. 7 is a top plan view of the design of FIG. 1; and,

FIG. 8 is a bottom plan view of the design of FIG. 1.

The equally spaced broken lines in FIG. 2 represent claimed perforation lines.

The long and short dashed lines in the drawings represent unclaimed environmental subject matter and form no part of the claimed design.
